(57) **CLAIM**

The ornamental design for a gravity feed paint tray system, as shown.

DESCRIPTION

FIG. 1 is a front elevational view thereof;

FIG. 2 is a top plane view thereof;

FIG. 3 is a right side elevational view thereof;

FIG. 4 is a left side elevational view thereof;

FIG. 5 is a bottom plane view thereof;

FIG. 6 is a perspective view thereof; and,

FIG. 7 is a section view through line 7—7 showing my new design.
